UNITED STATES PATENT OFFICE.

EDWARD E. CLEMENT, OF WASHINGTON, DISTRICT OF COLUMBIA, ASSIGNOR TO EDWARD F. COLLADAY, OF WASHINGTON, DISTRICT OF COLUMBIA.

RADIO BROADCAST DISTRIBUTING SYSTEM.

Original application filed May 21, 1925, Serial No. 31,928. Divided and this application filed June 25, 1926. Serial No. 118,488. Renewed March 8, 1927.

My invention relates to systems of radio broadcast distribution and more particularly to a relaying system for organized distribution. The present application is a division 5 of my copending application Serial No. 31,928, filed May 21, 1925.

Very briefly stated, this system includes subdivision of the ultimate units or subscribers' stations into local groups in local 10 areas, each group related to a local or regional distributing station; the grouping of these regional stations according to districts and the relation of the district stations to a central master station. There may be 15 more intermediate steps or stations interposed between the subscriber's control or regional station and the central master station and there may be direct connection between the said regional stations and the 20 central master station, but these possible variations will be apparent from the detailed description and do not change the principle involved. In any case, for purposes of distribution, the central master station 25 broadcasts to the district master stations on divisional carrier wave frequencies, each of the district master stations broadcasts to its constituent regional central stations on a fixed carrier wave frequency, and each local or regional central station broadcasts to the subscribers in its local area on a common fixed carrier wave frequency.

Thus it will be apparent that the first 30 characteristic feature of the system is that of sending from each center to the class or order of centers next above or below it, on a fixed carrier wave frequency or frequencies allotted permanently to said next higher or lower order of stations. If we call the central master station of the entire system, A, and call the district master stations B, the local or regional distributing stations C; and the subscribers' instruments in general D, then we may say that A transmits to B on B frequency, B transmits to C on C frequency, and C transmits to D on D frequency, of the respective carrier waves. For information that goes through from A to D, or that goes through from B to D, as 45 well as information originating with C, original modulations are actually repro-

duced in the instruments at D, by means which will be described. The simplest way to do this is by double modulation, which also enables easy change of carrier wave frequency at the intermediate or relaying stations. 55

My invention is illustrated in the accompanying drawings, in which:

Fig. 1 shows symbolically an arrangement of double modulating and transmitting equipment at the A or master station of the system for matter originating there. 60

Fig. 2 shows symbolically equipment for the B stations, by means of which the primary carrier waves transmitted from the apparatus of Fig. 1 may be demodulated and the intermediate frequency waves or envelope modulated upon a new carrier wave C. 65

Fig. 3 shows symbolically apparatus similar to that in Fig. 2, but intended to be located at the local or regional distributing stations C, receiving, therefore, on the C wave frequency, and transmitting on the D or subscriber's frequency. 70

Fig. 4 shows symbolically a subscriber's set adapted to receive on the D frequency, to demodulate the short carrier wave, and then to demodulate the intermediate frequency carrier wave, so as to produce audio waves as its output. 75

Fig. 5 is a similar circuit diagram of the apparatus shown in Figs. 2 and 3, which is the same in construction and arrangement, but differently tuned according to the station B or C, at which it is located. 85

Fig. 6 is a circuit diagram of a subscriber's receiving set arranged for selection through double modulation.

Referring now to Figs. 1 to 4 inclusive, and first to Fig. 1, I have shown therein an arrangement for originating broadcast transmission at the head or master station A. The purpose is double modulation, by first modulating by means of a telephone transmitter upon a long wave, and then modulating the long wave upon a short carrier wave of suitable frequency to be received at the stations B. It goes without saying, that this same arrangement of apparatus will be found at each of the other central stations B and C. In order that 90

this apparatus may also be employed for radio broadcasting of material brought into the stations over wired trunks, I show a jack J^{10} connected through an amplifier to 5 switch contacts which may be connected through switch arms to the primary of the transmitter induction coil, 302, the secondary of which is connected to the modulator of the generating and transmitting set. 10 Thus a trunk line or even a subscriber's wire may be plugged on to the modulator through the amplifier by means of jack J^{10} .

Fig. 2 shows a relay apparatus primarily intended for use at stations B and C, but 15 which will also be used at master station A. Fig. 3 shows identical apparatus, except for the jacks 303 and 304, the purpose of which will be presently explained. These jacks can be used in the circuit of Fig. 3 if 20 desired.

The function of the apparatus of Fig. 2 is to take double modulated waves at the frequency allotted to the receiving station, demodulate the short wave carrier so as to 25 produce modulated intermediate frequency waves which are then passed through a tuned amplifier 305 to a modulator 306, by means of which they are modulated on a primary or short wave carrier of a frequency suitable for the next lower order of 30 receiving stations, in this case C stations. The short waves thus modulated are then radiated.

By means of the jack 303, intermediate 35 frequency or long waves modulated may be taken off a trunk and passed through the amplifier 305 to the modulator 306 and thence radiated as before. Also, by means of the jack 304 intermediate frequency or 40 long waves modulated which have passed through the demodulator 307 and the amplifier 305 may be forthwith placed upon the wire trunk lines for transmission to other stations. These extensions should be available at each stage in the system, and I consider it original with me to provide means 45 for affecting these combinations of super-audio frequency modulated waves transmitted either from wires to radio carrier or 50 from radio carrier to wires without change either in the intermediate frequency waves or in their modulations, and shall claim the same accordingly. This is one essential feature of the present system, which it is believed should be adhered to in any system 55 of organized broadcasting, i. e. that when an original modulation is once made, the wave train carrying that modulation should be preserved unchanged throughout its entire 60 course from point of origin to the listener's ears.

Referring to Fig. 4, this shows typically a subscriber's apparatus for taking double modulated waves sent out from the stations 65 of any of the preceding three figures, and

demodulating the same so as to recover the original audio modulations make them apparent. There are two units, one a demodulator of the short carrier wave, which produces the long intermediate frequency wave 70 carrying the original audio modulations, and passes these to the second demodulator, which demodulates the intermediate waves and passes the audio waves to the telephone receiver shown at the right of the figure. 75 This method if shown in detail in my copending application referred to above, where the circuit arrangement of such a double demodulator is illustrated in full.

The apparatus shown in Figs. 2 and 3, 80 is intended to receive a double modulated carrier wave such as that radiated from the antenna in Fig. 1, demodulate the same and reimpose the long wave or intermediate frequency, with its modulations, upon another 85 short wave carrier which in the apparatus of Fig. 2 is supposed to be the carrier wave of the frequency allocated to stations C, while in the apparatus of Fig. 3 this is supposed to be the carrier wave of a frequency 90 allocated to the subscribers' stations D. Glancing at the four figures, 1, 2, 3 and 4, it will be observed that from the original modulation due to the transmitter 150 to the final demodulation by the intermediate wave 95 demodulator in Fig. 4, the same intermediate long wave carrier, and the same audio modulations thereof, are maintained intact and unmodified, being merely passed along by relaying from station to station on short 100 carrier waves, or an equivalent of the carrier waves.

The apparatus in Fig. 2 and that in Fig. 3 is identical except for the tuning of the transmitted carrier wave. The description 105 of one therefore will suffice for both.

Referring to Fig. 5, which is a detailed circuit applicable to both these figures, 54 is the receiving antenna coupled at 174 to the grid circuit of the detector 170, whose plate 110 circuit is connected through a tuned filter coupler 175 to the grid circuit of the amplifier tube 171, whose plate circuit is connected through the transformer 176 to the grid circuit of the modulator tube 172, which in 115 turn has the usual Heising connections 178—179 to the circuit of the oscillator tube 173; the radio choke coil 178, the power battery B^{14} and the magnetic choke coil 177, being arranged as usual. The grid and plate 120 of the oscillator tube 173 are connected to the antenna inductance coil 180, which with the usual tuning condenser 180^a is included in the antenna circuit 55. Filament batteries B^{11} , B^{13} , and B^{15} , and plate batteries 125 B^{12} and B^{16} are located as usual. As thus described, the assemblage constitutes a relay set which will take in the modulated long waves on a short wave carrier, and retransmit them on a carrier of different frequency, 130

without demodulating or disturbing the modulations of the intermediate or long wave. In order that these long waves may be transferred from the first detector circuit to 5 trunks and in order that modulated long waves brought in by trunks may be placed on the radiating antenna 55, I provide connections symbolized as jacks J^6 — J^{90} . The jack J^6 has its springs connected to the terminals of the coupler 175, and these springs normally rest on contacts connected in the grid circuit of the modulator tube 172. Trunks such as 10 50 and 51 terminate on jacks J^6 and J^7 and are adapted to be interconnected with each other or with the jacks J^6 and J^{90} by plugs 15 and cords as indicated at P^5 and P^6 . By plugging either one of the trunk jacks J^6 or J^7 onto jack J^6 , the corresponding trunk line 20 will be connected to the tuned filter coupler 175, whose windings are simultaneously disconnected from the detector tube 170. Thus 25 modulated carrier current at the same frequency as the intermediate waves used in the radio side of the system, will come over the trunk line 50, for example, through the jacks J^6 and J^9 and plugs P^5 and P^6 , and so to the coil 175, whence the long waves 30 will pass to the grid circuit of the amplifier tube 171, to be amplified and then sent through the modulator and oscillator circuits of tubes 172 and 173. Any incoming 35 trunk material can in this way be put "on the air" at any station having the relay apparatus of Fig. 8 or the equivalent thereof. For reverse operation, by plugging either 40 one of the trunk jacks J^6 or J^7 on to the jack J^{90} , the corresponding trunk, as 57 for example, becomes connected through plug P^6 and plug P^5 to plug J^{90} and therethrough to the coil 176, whose primary winding is 45 simultaneously disconnected from the grid circuit of the modulator tube 172. The incoming modulated short carrier waves received on the antenna 54 will pass through the detector 170 and demodulation of the primary carrier long intermediate frequency 50 waves will be passed through the filter coupler 175, amplified by the tube 171, and so communicated through the coupler 176 to the cord circuit and jacks, directly 55 to the trunk line 51. In this way, material can be taken "off the air" at any time and put on the trunks by simply obliterating the primary carrier wave. It 60 it to be understood that by varying the tuning of the couplers, long waves of any frequency can be taken from or fed onto the trunks. Thus, the mechanism shown in Fig. 5 contains within itself all the elements necessary for transfer from the receiving antenna to a trunk or trunks, of 65

modulated superaudio carrier current; for transfer of modulated superaudio carrier current or waves from a trunk or trunks by modulation on to a short carrier wave, to the antenna 55 for radiation; and for transfer 70 from trunk to trunk between the stations of audio or superaudio modulated waves or carrier current. It will be understood of course that the mechanism and circuits described are typical only, and in this specific 75 form are used for purposes of definition and not of limitation. I consider the arrangement and combinations shown in Fig. 5 to be new and original with me and shall claim the same accordingly. 80

A simple form of circuit arrangement for the subscriber's receiving set symbolized in Fig. 4 is that shown in Fig. 6. This comprises a receiving antenna 28 coupled to the input circuit of a detector tube 30 tuned to 85 the primary wave and a second detector tube 31 having its input circuit coupled through a filter coupler 33 to the output or plate circuit of the first detector 30, the filter coupler 33 being tuned to the intermediate 90 frequency. The second detector 31 of the subscriber's set has its output circuit coupled through an audio transformer 34 to the input circuit of an amplifier tube 32 whose output circuit is coupled through 95 a transformer 35 to a loud speaker 36. The usual "A" and "B" batteries are provided as indicated at A_1 and B_1 , respectively, the "A" battery lead 25 being connected to the filament bus 43 through a filament 100 switch h .

What I claim is:

1. In an organized system of radio broadcast distribution, means for transmitting a short primary carrier wave modulated with 105 a relatively long intermediate frequency carrier wave and this modulated in turn with an audio signal, and means for relaying the same comprising a primary demodulator and a modulator transmitter, for 110 transferring the modulated intermediate frequency or long carrier wave without change in its characteristics or modulations to a different short carrier wave, together with a wire circuit tuned to said intermediate frequency extending between stations and connecting the primary demodulator at one station with the modulator transmitter at another station. 115
2. In an organized system of radio broadcast distribution, a relay transmitter for double modulated waves comprising a demodulator, an amplifier, a modulator and an oscillator transmitter in combination therewith, together with means for connecting a wire circuit between the receiving demodulator and the amplifier so as to cut off the demodulator and connect with the input circuit of said amplifier or between 120 said amplifier and the transmitting modula- 125

tor so as to cut off said modulator and connect to the output circuit of said amplifier, for transferring modulated long waves from said wire circuit to the radio transmitter or 5 from the demodulator to said wire circuit, whereby intermediate frequency or long carrier waves may be relayed not only from radio carrier wave to radio carrier wave, but from radio carrier wave to wires and vice versa.

10

In testimony whereof I hereunto affix my signature.

EDWARD E. CLEMENT.
